UNITED STATES PATENT OFFICE.

HARRY S. GOODMAN, OF CHICAGO, ILLINOIS.

SAVINGS BANK.

Application filed July 17, 1925. Serial No. 44,234.

My invention relates to savings banks and has for its object the provision of a simplified structure for such a bank which is made in two separable sections easily separated through the agency of a key or similar means, and which sections are easily and readily placed in their proper closed relationship and automatically locked without the aid of a key or similar means.

I will describe my invention more in detail by referring to the accompanying drawings, in which

Fig. 1 is a perspective view showing my improved savings bank in its closed condition;

Fig. 2 is a partial sectional view on line 2—2 of Fig. 3;

Fig. 3 is a sectional view on line 3—3 of Fig. 2;

Fig. 4 is a perspective view on the cap section;

Fig. 5 is a similar view of the base and shell section, and

Fig. 6 is a fragmentary sectional view illustrating the key unlocking means.

The savings bank is constructed of two parts, the base and shell section 10, as shown more clearly in Fig. 5, and the cap section 11, as illustrated more clearly in Fig. 4.

When these two parts are juxtaposed into their closed condition and locked, they form the completed savings bank as shown in Fig. 1.

My invention concerns itself primarily with the provision of means whereby these two sections may be placed together and actuated into their closed locked condition by means which operate substantially automatically to effect this end.

For this purpose, the base and shell section 10 has an inner end wall 12 and a side wall 13. An outer end wall 14 is provided to serve the purpose of strengthening these parts and holding them in their proper relationship, and also for purpose of design. The side wall 13 has three inwardly extending lugs 15 which are preferably punched out of the body of the material, and which form at their lower portions, cut metal edges.

These cut metal edges are designed to contact with cooperating elements provided upon the cap section, as will be presently explained. The inner end wall 12 also has a struck-up tongue 16 having a hole 17, which hole serves for the reception of the inner extremity 18 of a key 19. The key itself

is introduced through the side wall 13 through a key slot 20 provided for that purpose. The section 10 also has a spring pressed latch 21, which latch is pivoted about the rivet 22 and is forced upwardly into locking position by a spring 23 secured to the end wall 12 by the rivet 24. The lugs 15 are adapted to prevent longitudinal separation of the parts 10 and 11 and the latch 21 when in its locking position prevents radial movement between these two parts. The cap section 11 is provided with a downwardly extending flange or flanges 25, which flange is provided with three slits 26. These slits are so arranged that a portion of the metal underneath the slit, as shown for instance at 27, is pushed inwardly for the purpose of accommodating the lugs 15 when in their locking position so that these lugs 27, the flange 25 is bent inwardly as shown at 28 so that when the two parts 10 and 11 are brought together, the lugs 15 register with the parts 28 until the two sections are as close together as their structure permits, whereupon a slight rotation relatively between these sections causes the cut metal edges of the lugs 15 to ride underneath the cut metal edges of the slits 26 at the indented parts 27, thus to prevent straight longitudinal separation of these sections.

At the same time that these two sections are rotated relatively into such condition that longitudinal separation is prevented, an inwardly extending tongue 29 provided upon the cap section 11 rides over the tooth of the latch 21 into locking position so that thereafter the parts 10 and 11 cannot be rotated relatively in the opposite direction without the use of the key 19.

It will thus be apparent that the two sections 10 and 11 when originally in their separated conditions as shown in Figs. 4 and 5 may be placed in their interlocking position with the lugs 15 riding along the indentations 28 until their respective cut metal edges are aligned, whereupon a slight rotation is all that is necessary to lock the parts permanently in their closed locked condition.

Should it be desired to open the bank, then the key 19 is introduced and its tongue 30 rotated so as to press the latch 21 downwardly, whereupon the sections 10 and 11

may be reversely rotated to again align the lugs 15 with the indentations 28, whereupon a longitudinal separation of the two sections may be effected. The cap and shell 5 section 10 is also provided with a slot 31 in its side wall through which coins of the appropriate size may be inserted. This slot 31 registers with a similar slot 32 in the flange of the cap section 11 when the two 10 parts are in their locked position. The flange 25 is also provided with a spring guard 33 having a slot 34, which slot 34 is also of the appropriate size to permit the insertion of the desired coin. The slots 32 15 and 34 are relatively displaced so that they do not register.

From this it will be noted that if a coin is introduced, the action of introducing the coin will push the spring guard 33 inwardly 20 until it is in such position as to permit the coin to pass through both slots 32 and 34. After the coin is in position within the bank, the spring guard 33 snaps back into the position shown in Fig. 4 and prevents withdrawal 25 of the coin.

This structure thus provides an extremely simple device adapted for automatic closure and for very ready and easy separation through the aid of a key. Various modifications 30 may of course be made without departing from the spirit of my invention.

Having thus described my invention what I desire to claim and secure by United States Letters Patent is:

35 1. A savings bank having two separable sections, one of which constitutes a base and shell section, and the other of which constitutes a cap section, said cap section having inwardly extending portions, and interacting cut metal edges provided upon said portions and the shell portion of said first aforesaid section intermediate the ends thereof, said edges being adapted, when said sections are juxtaposed and relatively rotated, to interengage to prevent longitudinal separation of said sections.

40 2. A savings bank having two separable sections, one of which constitutes a base and cylindrical shell section, and the other of which constitutes a cap section, said cap section including a cylindrical flange thereon interfiting with said cylindrical shell section and having spaced inwardly extending portions, interacting engaging edges 45 provided upon said portions and struck out from the body of the shell portion of said first aforesaid section, said edges being adapted, when said sections are juxtaposed and relatively rotated to interengage to prevent longitudinal separation of said sections.

45 3. A savings bank having two separable sections, one of which constitutes a base and cylindrical shell section, and the other of

which constitutes a cap section, said sections having inwardly extending portions, the inwardly extending portions of said sections being slit to provide interacting cut metal edges adapted when said sections are juxtaposed and relatively rotated to prevent longitudinal separation of said sections, and a key-controlled lock on said sections to prevent relative rotation between said sections.

4. A savings bank having two separable sections, one of which constitutes a base and cylindrical shell section, and the other of which constitutes a cap section, said sections having inwardly struck portions providing grooves on one of said sections adapted to receive projections on the other of said sections by relative longitudinal movement of said sections, the walls of said inwardly struck portions being slit to provide interacting cut metal edges adapted, when said sections are juxtaposed and relatively rotated, to interengage to prevent longitudinal separation of said sections, and means to prevent relative rotation between said sections.

5. A savings bank having two separable sections, one of which constitutes a base and cylindrical shell section and the other of which constitutes a cap section, said sections having inwardly struck portions providing grooves on one of said sections adapted to receive projections on the other of said sections by relative longitudinal movement of said sections, the walls of said inwardly struck portions being slit to provide interacting cut metal edges adapted, when said sections are juxtaposed and relatively rotated, to interengage to prevent longitudinal separation of said sections and means to prevent relative rotation between said sections, the ends of the slits in one section engaging the edges of the projections in the other section to limit the relative rotation of the sections in one direction.

6. A savings bank having two separable sections, one of which constitutes a base and cylindrical shell section, and the other of which constitutes a cap section, said cap section having inwardly extending portions providing longitudinally extending grooves, slits extending transversely of said grooves providing means interacting with inwardly extending means provided on the shell portion of said first aforesaid section to prevent longitudinal separation of said sections when the same are juxtaposed and relatively rotated, and a key-controlled lock on said sections to prevent relative rotation between said sections.

In witness whereof, I hereunto subscribe my name this 26th day of June A. D., 1925.

HARRY S. GOODMAN.
